TYPEWRITING MACHINE

Walter S. Lemmon, New York, N. Y., assignor to
 International Business Machines Corporation,
 New York, N. Y., a corporation of New York

Application November 24, 1934, Serial No. 754,558

1 Claim. (Cl. 197—20)

This invention relates to automatically operated typewriting machines, and the principal object of the invention is the provision of simple and inexpensive means for selectively controlling the operations of the machine by means of an indicia record control means, or manually from the key board in the usual manner.

In this disclosure of the present invention for purposes of illustrating the principle of operation one type of indicia record control means will be embodied, and which is in part in the form of a tape, sheet, or ribbon on which characters or other indicia to be reproduced are represented by perforations to selectively operate the associated translating mechanism, one form of which as shown may be a conventional power operated typewriter.

It is an object of the present invention to provide sensing means to cooperate with the indicia record control means in such a manner that when a particular form of indicia is sensed, a circuit corresponding to the said indicia is energized to further control the associated translating mechanism.

Further and other objects of the present invention will be hereinafter set forth in the accompanying specification and claim and shown in the drawing which by way of illustration is what I now consider to be the best mode in which I have contemplated applying that principle. Other embodiments of the invention employing the same or equivalent principle may be used and structural changes made as desired by those skilled in the art without departing from the present invention and within the spirit of the appended claim.

In the drawing:

Fig. 1 shows a transverse sectional view of so much of a typewriting machine as is necessary to illustrate a preferred embodiment of the invention.

Fig. 2 shows a diagrammatic circuit diagram illustrating the preferred embodiment of the invention.

45 *Typewriter mechanism*

Referring now to Fig. 1, in the embodiment illustrated in the drawing, well known means are provided for actuating the type bars by power operated devices comprising a power driven roller 10.

A cam 11 is pivoted on one arm of a bell crank lever 12 pivoted in the frame, the other arm of which is operatively connected with one arm of a bell crank lever 13 by means of link 14. The

other arm of lever 13 is connected to the type bar (not shown) mounted to swing to and from printing engagement with a platen or a work sheet arranged thereon and need not be further described, being well known to those skilled in the art.

The lever 12 is actuated by the cam 11 when the latter engages the driven roller 10 to be operated thereby. The engagement of the cam 11 with the power roller is controlled automatically by means of the solenoid 18 connected to the key bar 17 by link 19. The cam 11 is resiliently engaged by a spring-pressed arm 20 which tends to turn it into engagement with the power driven roller or a stop 21 on a lever 22 pivoted on the bell crank 12 and normally arranged in the path of a lug 23 on the cam.

When the lever 22 swings to move its stop out of the path of the lug, the arm 20 swings the cam into engagement with the power roller to be actuated thereby to swing the bell crank 12 to actuate its connected mechanism. The lever 22 has an arm 24 which is provided with an offset projection 25 at its end which projects laterally through an opening in the bell crank 12 and engages the bifurcated lower end 26 of an arm 27 of a key lever 17 pivoted on the common rod 28 and linked to the solenoid 18. It is obvious then that energization of solenoid 18 in causing a key lever 17 to be depressed releases the revolubly mounted cam 11 to engage and be actuated by power roller 10 in turn operating bell crank 12 and its attached links to cause the associated mechanism such as the key bars or case shift mechanism to be operated.

It will be understood that the usual number of type bars and associated devices for operating them may be employed, although only one of them is illustrated herein for the sake of clearness.

40 *Sensing mechanism*

It was mentioned that automatic controlling means for selective operation of the typewriter is provided which in the preferred form is shown as a master sheet or roll 38 on which characters or other indicia to be translated into typewriting are represented by perforations 31 (Fig. 2).

The perforations are formed by any suitable means and are provided on a sheet or roll wide enough to contain a longitudinal series of perforations, evenly spaced, for the control of each element of the machine to be operated, namely the solenoids 18 of the typewriter.

45 A sensing mechanism is provided to cooperate

with the perforated sheet in such a manner that when a particular perforation is sensed, a circuit corresponding to the represented character is energized to control the typewriter accordingly.

5 The following brief description is sufficient since a more complete disclosure of the sensing device is made in my copending application Serial No. 743,208, filed September 8, 1934, and which as shown is provided with a horizontal transverse 10 conducting roller 32 which supports and feeds the elongated perforated sheet 30. A plurality of sensing brushes 33 are positioned so as to enable them to cooperate with the feed roller 32 when a perforation is sensed. The sheet 30 is 15 wide enough to contain a longitudinal series of evenly spaced perforations, the position of a single perforation on the sheet indicating the particular character representation. There are provided as many brushes 33 as there are perforation positions, that is, an individual brush for each perforation which is representative of a character or other indicia.

Therefore when the sheet is fed continuously to the sensing device by suitable means, such as 20 motor 34, and when the particular brush 33 senses its corresponding character perforation a controlling circuit will be completed to control the operation of the typewriter which will be described hereinafter.

30 Case shift mechanism

It is necessary to note at this time the provision made for operation of the carriage shift key of the typewriter. In order to record both upper 25 and lower cases, it is obvious that the shift key must remain in its designated or predetermined position for that period during which the corresponding type of recording is desired; for example, as is usually the method, when upper case 30 is desired the shift key must remain depressed for that particular period of upper case typing. The following is what is now considered the preferred method of effecting this procedure. The carriage shift sensing brush 33a upon engaging a 35 perforation in roll 30 indicating a desired shift of type case causes energization of magnet 40 to cause the cam wheel to be rotated so that its high surface forces contact blade 42 into engagement with contact 43, which is fully described in my copending application Serial No. 746,489, filed October 2, 1934, keeping said contacts closed to effect a carriage shift which operation will be explained hereinafter.

The carriage shift mechanism remains in the 40 operated position so long as contacts 42 and 43 are closed. Upon reception of another impulse energizing magnet 40 cam wheel 41 is stepped ahead to permit contact blade 42 to engage a lower surface of the cam wheel to disengage the 45 contacts 42 and 43, thereby restoring the carriage shift mechanism to its normal printing position. Since ratchet 44 is provided with two times the number of teeth as there are high surfaces on cam wheel 41, it is obvious that a single 50 operation of magnet 40 will cause contacts 42 and 43 to close and a second energization of the magnet will permit them to resume the position they occupy in the figure.

70 Operation

Upon closure of the switch 35, motor 34 is energized by the circuit including grounded battery 36, to rotate the feed roller 32 which is adapted to introduce the perforated sheet 30 between the 75 brushes and conducting roller 32. The individual

brushes 33 are connected to separate solenoids 18 and as mentioned hereinbefore adapted to sense a particular perforation column or position all of which represent the same corresponding character, that is the separate brush, its connected solenoid and the corresponding perforation column adapted to be sensed. Individual brushes 33 and the connected solenoids 18 and perforation positions are provided for each character representation.

10 Therefore the brushes 33 upon sensing the particular corresponding perforations 31 engage conducting roller 32 to complete circuits whereby current from grounded battery energizes solenoids 18 through contacts 45 closed at each sensing operation, by virtue of the grounded common contact 37 adapted to engage the roller 32 continuously.

15 Energization of solenoid 18 causes its corresponding key lever 17 to be depressed to release 20 the cam 11 and then actuated by power roller 10 to rotate the cam a half revolution which causes the bell crank lever 12 to operate its connected type bar, recording the character represented by the sensed perforation on sheet 30.

25 A cam wheel 46 is shown fixed on the conducting roller shaft, the purpose of which is to cut off the current from battery 36 to the solenoids 18 whenever a perforation is sensed and before the edge of the perforation is reached by the sensing 30 brush. Instead of deenergizing the energized solenoids 18 when the brushes 33 leave the perforation and are separated from the conducting roll 32 by the perforated sheet 30, the cam wheel 46 is adapted to break the contacts 45 before the 35 brushes 33 are disengaged from the conducting roll by the said sheet.

35 The cam wheel 46 is preferably an insulated member similar to cam wheel 41 and adapted to have its lower surfaces 47 so arranged on its periphery that when rotated synchronously with feed roll 32 by motor 34 they permit the contacts 45 to be engaged at the same moment the brushes 33 sense their particular perforations. It was 40 mentioned hereinbefore that the perforations 31 are evenly spaced so that the camming surfaces can be so positioned to be in synchronism with the sensing of the perforations. Before the brushes 33 disengage from the conducting roll 32 or in other words before the perforations are advanced to separate the brushes from the conducting roll, the high surfaces on the cam wheel 46 open the contacts 45 to break the established circuit from grounded contact 37, conducting roll 32, brush 33, solenoid 18, contacts 47 to grounded 50 battery 36, deenergizing the said solenoid.

45 When a carriage shift is desired for a change of type case the sensing brush 33a sensing its corresponding perforation energizes magnet 40 by the established circuit from grounded battery 55 36, now closed contacts 47, magnet 40, brush 33a, roll 32, grounded contact 37.

50 Energization of this magnet steps cam wheel 41 ahead to close the contacts 42 and 43 by the cooperation of the high surface of the wheel with the contact blade 42, thereby permitting current from grounded battery 36 to energize solenoid 18a which is connected to the shift key of the typewriter. The key shift solenoid remains energized until another shift perforation is sensed to energize magnet 40, and obviously maintains the shift key depressed to render the typewriter shift mechanism operative until the second energization of magnet 40 to disengage the con- 70 75

tacts 42 and 43 to deenergize solenoid 18a restoring the shift mechanism to normal position.

It is obvious that any number of typewriters can be operated at one time by having the corresponding solenoids of the additional machines connected, for example, in multiple to the corresponding circuits connected to the sensing brushes as shown in the dotted section in the figure.

- 10 The operation of the control or master roll 30 is controlled by means of a manually operated switch 35 so that its operation may be stopped when desired, and the machine operated manually when any insertion or additional matter is to be recorded. During such operation the bell crank levers 12 are actuated independently of the master sheet control by the manual depression of the key levers 17 to effect typing in the manner described.
- 20 While there has been shown and described and pointed out the fundamental novel features of the invention as applied to a single modification, it will be understood that various omissions and

substitutions and changes in the form and details of the device illustrated and in its operation may be made by those skilled in the art without departing from the spirit of the invention. It is the intention therefore to be limited only as indicated by the scope of the following claim.

What is claimed is as follows:

In a typewriting machine comprising a case shift instrumentality, control means therefor and connected thereto, the combination of a perforated record control sheet, sensing means comprising individual brushes cooperating therewith, electromagnetic means controlled by one of said sensing brushes and adapted to control the operation of said instrumentality control means, and means comprising cam controlled contacts connected to said instrumentality control means to render said instrumentality operative and inoperative upon successive energization of said electromagnetic means.
